(71) Applicant: **Caterpillar Inc.**, Peoria, IL (US)

(72) Inventors: **Eric Thomas Sinn**, Tremont, IL (US);
Douglas Charles Serrurier, Morton, IL (US); **Rammagy Yoeu**, Dunlap, IL (US)

(73) Assignee: **Caterpillar Inc.**, Peoria, IL (US)

(**) Term: **15 Years**

(21) Appl. No.: **29/851,868**

(22) Filed: **Sep. 1, 2022**

Related U.S. Application Data

(63) Continuation of application No. 29/824,077, filed on Jan. 21, 2022, now Pat. No. Des. 966,346, which is a continuation of application No. 29/758,758, filed on Nov. 18, 2020, now Pat. No. Des. 945,499.

(57) **CLAIM**

The ornamental design for an adapter for a ground engaging machine implement, as shown and described.

DESCRIPTION

FIG. 1 is a front perspective view of an adapter for a ground

engaging machine implement showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate structure or features which form no part of the claimed design.

The dot-dash broken lines illustrate boundaries which form no part of the claimed design.

1 Claim, 7 Drawing Sheets
